UNITED STATES PATENT OFFICE

HENRY F. WARDWELL AND WALTER C. BLADIN, OF CHICAGO, ILLINOIS

SIDE BEARING FOR RAILWAY CARS

Application filed October 21, 1927. Serial No. 227,690.

This invention relates to railway side bearings of the self-centering type.

The main objects of this invention are to provide an improved form of side bearing of the self-centering type which will keep itself drained of water at all times; to provide a bearing of this type which is strong, substantial, durable and economical to manufacture; and to provide an improved form of bearing housing in which can be used bearing rollers having square edges, such as result when the rollers are cut from a length of tubing or round bar.

An illustrative embodiment of this invention is shown in the accompanying drawing in which:

Figure 1 is a top plan view of the improved bearing, with the bearing roller in place therein.

Fig. 2 is a longitudinal elevation of the same, showing the wear plate for the roller in position above the bearing, a portion of the bearing housing being shown in vertical section as indicated by the line 2-2 of Fig. 1.

Fig. 3 is a section taken on the line 3-3 of Fig. 2 with the exception of the bearing roller, which is shown in elevation.

Fig. 4 is a section taken on the line 4-4 of Fig. 2.

Heretofore in the use of side bearings which are of general cup-shaped appearance, certain difficulties have been encountered, due to lack of drainage of the water which necessarily accumulates therein, and especially during the winter time when this water becomes frozen, thus preventing the bearing roller from properly functioning.

In the present invention, the bearing housing has been so designed that the concave bearing surface is of less width than the inside width of the housing, thus providing grooves at the sides thereof for carrying the water to the opposite ends of the housing wherein there is provided sumps from which the water is suitably drained by means of openings extending through the housing and communicating with the sumps.

In the construction shown in the draw-

ing, an elongated cup-shaped housing 1 is provided with semi-cylindrical end walls 2 and 3 having a vertical axis with respect to the bearing when it is mounted in position on a railway truck bolster. The upper surface 4 of the bottom 5 of the housing is concave so as to cause the self-centering of the bearing roller 16, and is of narrower width than the inside width of the housing, forming grooves 4A and 4B along the opposite sides thereof for carrying away water. The semi-cylindrical end walls 2 and 3 have an inside diameter less than the width of the upper surface 4 of the bottom of the housing, thus forming the spaced abutments 17, 17 and 18, 18 which are spaced from the respective ends of the surface 4 and afford stops to limit the travel of the roller 16. The ends of the concave surface 4 terminate in spaced relation to the ends of the housing 1 so as to provide substantially flat bottomed combination drain sumps and bolt or rivet head receiving recesses 6 and 7, the bottom surfaces of these sumps being on substantially the same plane as the lowermost point of the concave bearing surface 4.

The sumps 6 and 7 are provided with vertically disposed bolt or rivet holes 8 and 9, respectively, extending through the bottom of the housing, for receiving the usual retaining means. The cylindrical end walls 2 and 3 are provided with drain holes 10 and 11, respectively, the lower sides of which are on substantially the same plane as the floor of the sumps 6 and 7 so as to keep the sumps drained free of water at all times.

A wear plate 12 is provided in the usual manner for contacting with the bearing roller 16 and it is adapted to be attached to the car body in the customary manner.

From the foregoing it will be observed that we have provided a side bearing for railway cars in which the substantially rectangular housing having the bottom, side and end walls is so arranged that the raised concave surface 4, which is spaced from the side walls thus forming the grooves 4A and 4B, is also arranged to terminate short of the abutments 17, 17 and 18, 18. These

abutments are arranged in vertical spaced relation and lie beyond the ends of the runway. These abutments, which are reinforced by the semi-cylindrical end walls 2 and 3, are spaced apart a less distance than the width of the roller and runway so that, when the roller reaches the ends of its travel, it engages the abutments at spaced points affording a relatively large space between 10 these abutments which is out of contact with any wall. This prevents the accumulation of snow and ice between the end walls and the roller and prevents freezing of the roller in one of the endmost positions of its 15 travel. Thus the cylindrical bearing surface of the roller which may contact with the abutments 17 or 18, as the case may be, is, under these conditions restricted to a limited surface of contact and thus the relatively 20 small amount of snow or ice which might possibly collect at these points of contact would not be sufficient to hold the roller against freedom of movement.

The invention overcomes one of the main 25 difficulties with side bearings, particularly where they are applied to refrigerator cars which sometimes must stand for relatively long periods of time on sidings or curves or in positions in which the truck is swung at 30 an angle to the body of the car, this resulting in the drain water from the refrigerator car flowing into the bearing and, if not promptly drained therefrom, freezing in position and preventing movement of the 35 roller in its proper functioning.

In the operation of the side bearing, the grooves 4A and 4B carry any water which tends to accumulate in the center of the bearing out into the sumps 6 or 7, from which it 40 drains through the drain openings 10 and 11, thus keeping the bearing from retaining any appreciable amount of water at any time.

Another feature of the grooves 4A and 4B is that they permit the use of a roller cut from a length of tubing or round bar, the square edges of which would ordinarily 45 cut into the fillet of the housing.

Although but one specific embodiment of 50 this invention has been herein shown and described, it will be understood that details of the construction shown may be altered or omitted without departing from the spirit of this invention as defined by the following claim.

We claim:

In a side bearing for railway cars, an 55 elongated rectangular housing having bottom, side, and end walls, said bottom wall 60 having a raised upper surface provided with a depression at its medial portion to form inclined runways terminating short of the ends of said bottom wall, and said runways 65 having the margins thereof spaced from the side walls to afford drain grooves extending

to the ends of said housing, said end walls being semi-cylindrical in horizontal cross section and shaped to afford vertical spaced abutments lying beyond the ends of said runways, said end walls forming end chambers in said housing, and said abutments being reinforced by said semi-cylindrical walls, and projecting toward each other to a distance less than the width of said runways so as to lie in the path of a bearing member mounted on said runways, the bottom wall having apertures in said chambers for receiving fastening members, drain ports in said semi-cylindrical walls at the junction thereof with the bottom wall and 70 in communication with said grooves, and a cylindrical bearing member riding on said raised upper surface and runways and limited in its travel by engagement of its cylindrical bearing surface with the vertical 75 abutments formed adjacent to said end walls, engagement of said cylindrical member with said abutments by virtue of the termination of said runways and the position of said abutments being limited to relatively small areas of contact between the cylindrical member and said abutments for preventing the accumulation of moisture or ice adjacent thereto, tending to prevent free movement of said cylindrical bearing member. 80

Signed at Chicago this 30th day of Sept. 1927.
